UNITED STATES PATENT OFFICE.

CLEMENT SCHWINGER, OF MANILA, PHILIPPINE ISLANDS.

PROCESS OF MAKING ARTICLES OF VEGETABLE SHELL.

1,115,342.

Specification of Letters Patent.

Patented Oct. 27, 1914.

No Drawing.

Application filed July 22, 1913. Serial No. 780,606.

To all whom it may concern:

Be it known that I, CLEMENT SCHWINGER, a subject of the Emperor of Germany, and a resident of Manila, in the Philippine Islands, have invented a new and useful Improvement in Processes for Making Articles of Vegetable Shell, of which the following is a specification.

This invention relates to the manufacture of articles out of cocoanut shell, or other hard vegetable shell, especially to buttons and the process of manufacturing such buttons. Cocoanut shell is peculiarly well adapted for the manufacture of buttons, since it has a very hard, firm, tough body, not easily broken; but in order to commercially make such articles special treatment of the shell is required. The larger percentage of the buttons are required to be colored by immersing in liquid dye, but in this treatment the time of immersion must be shortened to a minimum, for if the buttons are left too long in the solution the fibers or "veins" of the shell have a tendency to become loose and fall out, which would leave the faces of the buttons with ugly grooves and furrows. The polishing of the buttons has also to be effected in a particular manner. It is to these treatments, and the rendering of the manufacture of said buttons in large quantities inexpensive that my invention is directed; and I accomplish the ends in mind in the manner herein described.

The raw shells, in the first place, must have the soft tissue and loose fibrous matter removed from their faces by any convenient means. Then the shells are cut into blanks or disks of convenient size which are fed to automatic shaping and forming machines, commonly called "automatics" by which the buttons are finished as far as their shape and form is concerned. The buttons are then put in a revolving oven of any convenient type, and herein are subjected to a temperature of about 100 degrees Fahrenheit for a period of about an hour; this treatment having for its purpose to open the pores of the material so as to permit the dye to readily and thoroughly penetrate. The buttons are then taken from the oven and thrown into boiling liquid dye (anilin being generally used) and are allowed to remain in this solution just long enough to become thoroughly dyed as desired. This operation is relatively quickly accomplished, because of the condition in which the but-

tons are previously placed as above mentioned. The buttons are then taken from the dye and spread out to dry, when they are ready for polishing. The latter operation is accomplished by placing the buttons in a "tumbling barrel" or shakers containing shavings thrown off by the cocoanut shell in the process of "facing" them in the automatics; and to such shavings there is added, and intermixed, powdered stearin or stearic compound, or other suitable pore-filling and surface-polishing compound. In being tumbled about in such polishing material the minute pores of the shell become filled with the stearin, and the finished button is kept clean and bright. By this treatment the buttons acquire a dull finish.

If a high polish is desired, the buttons have to be polished singly by placing them in a revolving chuck and polishing by hand with a cloth dipped in dry, powdered stearin or stearic compound, or other suitable pore filling and surface polishing compound.

The expression "dye" is to be understood as including any coloring agent. The expression "stearic compound" refers to some compound of which stearin in some form is included.

I claim:

1. The process of making articles out of vegetable shell which consists in first producing a blank by removing the husk and soft tissue from the shell, then forming the article out of the blank, then subjecting the formed article to a temperature of about one hundred degrees Fahrenheit, then immersing the article in a liquid dye, then drying the article, and then finishing by tumbling the article in a mixture of fibrous material and a powdered stearic compound.

2. The process of making articles out of cocoanut shell which consists in first producing a blank by removing the husk and soft tissue from the shell, then forming the article out of the blank, then subjecting the formed article to a temperature of about one hundred degrees Fahrenheit, then immersing the article in a liquid dye, then drying the article, and then finishing by tumbling the article in a mixture of fibrous material and powdered stearin.

3. The process of making articles out of cocoanut shell which consists in first producing a blank by removing the husk and soft tissue from the shell, then forming the article out of the blank then subjecting the

formed article to a temperature of about one hundred degrees Fahrenheit, then immersing the article in a liquid dye, then drying the article, and then finishing by tumbling the article in a mixture of cocoanut shavings and a powdered stearic compound.

4. The process of making articles out of cocoanut shell which consists in first producing a blank by removing the husk and soft tissue from the shell, then forming the article out of the blank, then subjecting the formed article to a temperature of about one hundred degrees Fahrenheit, then immersing the article in a liquid dye, then drying the article, and then finishing by tumbling the article in a mixture of cocoanut shavings and powdered stearin.

5. In the art of making articles out of vegetable shell, the process of finishing which consists in tumbling the article in a mixture of fibrous material and a powdered stearic compound.

6. In the art of making articles out of cocoanut shell, the process of finishing which consists in tumbling the article in a mixture

of cocoanut shavings and a powdered stearic compound.

7. In the art of making articles out of cocoanut shell, the process of finishing which consists in tumbling the article in a mixture of cocoanut shavings and powdered stearin.

8. The process of making articles out of cocoanut shell which consists in first producing a blank by removing the husk and soft tissue from the shell, then forming the article out of the blank, then subjecting the formed article to a temperature of about one hundred degrees Fahrenheit, and then immersing the article in a liquid dye.

9. The process of making articles out of cocoanut shell, which consists in first producing a blank by removing the husk and soft tissue from the shell, then forming the article out of the blank and finishing by tumbling the article in a mixture of cocoanut shavings and a powdered stearic compound.

CLEMENT SCHWINGER.
